UNITED STATES PATENT OFFICE.

JOHN C. RINGE, OF STRATFORD, CONNECTICUT, ASSIGNOR TO THE SINGER MANUFACTURING COMPANY, OF ELIZABETH, NEW JERSEY, A CORPORATION OF NEW JERSEY.

SEWING MACHINE.

Application filed December 10, 1919. Serial No. 343,792.

To all whom it may concern:

Be it known that I, JOHN C. RINGE, a citizen of the United States, residing at Stratford, in the county of Fairfield and State 5 of Connecticut, have invented certain new and useful Improvements in Sewing Machines, of which the following is a specification, reference being had therein to the accompanying drawings.

10 This invention relates to improvements in sewing machines of the class commercially termed "lock-stitch" wherein there is employed an upper or needle-thread which, in the formation of the stitch, is concatenated 15 with an under or bobbin-thread located in a suitable bobbin-case carried by the loop-taker, and has for its object to provide improved means for passing a loop of needle-thread about a mass of under thread, and 20 to this end the bobbin-case is provided with a stop-lug and a stop-flange, the former co-operating with suitable lugs depending from the throat-plate and the stop-flange with an 25 adjustably secured stop-finger, said dependings lugs and flange cooperating, through vertical movements of the loop-taker, to alternately restrain the bobbin-case from rotation and effect positive openings for the 30 passage of the thread-loop about the mass of under thread, as will be more fully explained hereinafter.

Referring to the drawings, which form a part of the specification, Fig. 1 is a view in front side elevation of a sewing machine 35 equipped with the present invention. Fig. 2 is an under side view of Fig. 1. Fig. 3 is a view in cross-section of the bed-plate illustrating the fabric-feeding and looper-actuating mechanism in full lines. Fig. 4 is a 40 plan view of a portion of the bed-plate, its needle-plate and the feed-dog, together with the under stitch-forming mechanism located directly below the back slide-plate. Fig. 5 is an edge view of the needle-plate. 45 Fig. 6 is a view in perspective of the bobbin-case stop-finger. Fig. 7 is a detached view of the means employed for giving to the looper its vertical movement.

Referring to the figures 1 represents the 50 bed- or cloth-plate of the sewing machine upon which is mounted the bracket-arm comprising the standard 2 and arm-bracket 3 into which is suitably journaled the usual main or needle-bar actuating shaft (not 55 shown) provided with the band-wheel 4 and

at its forward end with a suitable link (not shown) operatively connected with the needle-bar 5 for giving to the latter its vertical or stitch-forming movements. 6 denotes the cloth-presser bar provided with 60 the cloth-presser 7, 8 one form of commonly employed needle-thread take-up and 9 and 10 the needle-thread tensioning mechanism and needle-thread guides, respectively.

11 denotes a pulley suitably secured to the 65 looper-actuating shaft 12 journaled in suitable bearings located below the bed-plate, said shaft receiving rotary movements through a belt 13 and suitable pulley (not shown) corresponding to the pulley 11, and 70 at its forward end journaled in a bushing 14 suitably secured in the frame supporting lug 15.

16 represents the loop-taker bracket adjustably secured to the under side of the 75 bed-plate by screw 17 and provided with a bearing lug 18 and securing lug 19 into which latter is secured, by pinch screw 20, the bearing bushing 21 further held against accidental movement by the screw 22 80 threaded into the frame-lug 23. 24 denotes a spiral gear suitably secured on the shaft 12 and meshing with a like gear 25 having a hub 26, later to be referred to, said gears being of the ratio of two-to-one, thus giving 85 to the gear 25 two rotations to one of the looper-actuating shaft 12.

27 denotes the feed rock-shaft having suitably secured upon its rear end a crank-arm 90 28 to which is pivotally attached a feed connection 29 whose upper end is pivotally connected to one form of commonly employed feed-lever (not shown) operated from an eccentric (not shown) carried by the needle-bar actuating shaft, said eccentric and bell-crank-lever also acting, through a suitable rock-shaft (not shown), to transmit lateral movements to the needle. As the above referred to feed and needle-actuating elements are common to many commercial sewing 95 machines it is deemed sufficient to refer to such elements without including them in the figures. For a further understanding of the cooperation of the feeding and needle-actuating elements see U. S. Patent No. 100 929,761, August 3, 1909, to C. F. Gray. The forward end of the rock-shaft 27 is provided with a yoke comprising the lugs 30 and 31 and cross-bar 32, the latter shown in dotted lines only, Fig. 2, and on said cross-bar is 110

pivots mounted one end of a feed-dog carrying bar 33 provided with a suitably secured feed-dog 34, and suitably secured to and depending from said bar 33 is a feed-dog lifting fork 35 in engagement with an eccentric 36 fast on the looper driving shaft 12. From the foregoing it will be understood that through the connections pointed out feed movements are transmitted from 10 the main-shaft to said feed-dog.

37 denotes the needle- or throat-plate suitably secured upon the bed-plate and provided with the feed-dog opening 38, the feed-dog being provided with a needle-opening 15 39 to accommodate the lateral movements of the needle in the direction of seam formation. The present invention is in no way limited to whether or not the needle is moved laterally, and accordingly, further 20 reference to such manner of control is unimportant. 40 and 41 denote the front and back slide-plates respectively.

Referring now to the more important inventive features in construction, 42 represents the loop-taker shaft mounted to rotate 25 and to be moved endwise in the bearing 43 of the bracket 16 and bushing 44 suitably secured in the lug 18 of said bracket, and upon the upper end of said shaft is suitably 30 secured the loop-taker 45 into which is suitably journaled the bobbin-case 46 provided with the bobbin 47 which, in turn, is provided with a mass of under thread 48, said bobbin-case being provided with a stop-lug 49 and stop-flange 50, said lug cooperating 35 with the notch 51, at the under side of the needle-plate, to, at certain times, restrain the bobbin-case from rotation and the flange 50 to, at other times, cooperate with 40 the free end of the adjustably secured stop-finger 52 for the like purpose.

53 denotes a looper-actuating eccentric carried by the looper-actuating shaft 12 and 45 54 an eccentric connection one end of which is provided with a strap 55 encircling said eccentric and at its opposite end pivotally connected to a rock-lever 57 whose free end is forked and internally provided with pins 58 which track a groove 59 in the lower 50 end of the loop-taker shaft 42, the latter being provided with a slot 60 which is entered by the inner end of a screw 61, the latter acting, through its connection with said slot, to transmit from the gear 25 rotary movements to said looper-actuating shaft and permit the latter to be moved vertically to place the loop-taker in different horizontal planes.

In the operation of the machine, supposing the needle to have been slightly raised 60 from its limit of downward movement and the loop-seizing point 62 of the loop-taker having passed into the needle-loop the further action of the needle and loop-taker will 65 cause the latter to operate and carry the loop

of needle-thread about the bobbin-case, and to free the loop from engagement with the stop-lug 49, the latter, by the action of the eccentric 53 through the connections pointed out, moves below the walls comprising the notch 51 in the needle-plate, thus providing a free passage for the loop in its travel about the first half of the bobbin-case, such movement of the loop-taker bringing the lug 50 of the bobbin-case in contact with the free 75 end of the finger 52, thus restraining the bobbin-case from rotation at such time as the lug 49 is out of engagement with the walls of said notch, and as the loop approaches the finger 52 the eccentric 53 acts, 80 through the connections above referred to, to elevate the loop-taker and with it the lug 50 out of engagement with the finger 52 effecting an opening for the loop and at the same time bringing the lug 49 within the 85 notch 51, thus effecting positive openings for the travel of the loop while restraining the bobbin-case from rotation by the action of the loop-taker, followed by an idle rotation of the loop-taker while the needle is 90 completing the stitch-formation and returning to its position of loop-formation.

Having thus set forth the nature of the invention, what I claim herein is—

1. In a stitch-forming mechanism for 95 sewing machines, in combination, a needle, means for reciprocating said needle, a loop-taker complementary to said needle in the formation of stitches, means for rotating said loop-taker, a thread-case journaled in 100 said loop taker, means for restraining the thread-case against rotation with said loop-taker, and means for bodily reciprocating said loop-taker and the thread-case carried thereby to provide a free passage for the 105 needle-thread loop past said restraining means.

2. In a stitch-forming mechanism for 110 sewing machines, in combination, a needle, means for reciprocating said needle, a loop-taker complementary to said needle in the formation of stitches, means for rotating said loop-taker upon a substantially vertical axis, a thread-case journaled in 115 said loop-taker, means for restraining the thread-case against rotation with said loop-taker, and means for bodily reciprocating the loop-taker in the direction of its axis of rotation to provide a free passage for the needle-thread loop past said restraining 120 means.

3. In a stitch-forming mechanism for 125 sewing machines, in combination, a needle, means for reciprocating said needle, a loop-taker complementary to said needle in the formation of stitches, means for rotating said loop-taker, a thread-case journaled in 130 said loop-taker, primary means for restraining the thread-case against rotation with said loop-taker, means for bodily recipro-

- cating said loop-taker and the thread-case carried thereby to release the primary restraining means from effective action, and supplemental restraining means effective upon release of said primary restraining means.
4. In a stitch-forming mechanism for sewing machines, in combination, a needle, means for reciprocating said needle, a loop-taker complementary to said needle in the formation of stitches, a thread-case journaled in said loop-taker, a loop-taker actuating shaft, means for rotating said loop-taker from said actuating shaft, an eccentric carried by said actuating shaft, and operative connections intermediate said eccentric and said loop-taker to impart bodily reciprocating movements to the latter.
5. In a stitch-forming mechanism for sewing machines, in combination, a needle, 20 means for reciprocating said needle, a loop-taker complementary to said needle in the formation of stitches, means for rotating said loop-taker, a thread-case journaled in said loop-taker, means for restraining the 25 thread-case against rotation with said loop-taker, means for bodily reciprocating said loop-taker and the thread-case carried thereby to release the thread-case restraining means from effective action, a stationary 30 stop-finger, and a stop-flange carried by said thread-case brought into effective engagement with said stop-finger upon release of said restraining means.
- In testimony whereof, I have signed my 35 name to this specification.

JOHN C. RINGE.
